UNITED STATES PATENT OFFICE.

HERMAN WESTLING, OF HUDSON, MASSACHUSETTS.

OVERSHOE.

1,339,994.

Specification of Letters Patent. Patented May 11, 1920.

Application filed February 2, 1920. Serial No. 355,740.

To all whom it may concern:

Be it known that I, HERMAN WESTLING, a citizen of the United States, and resident of Hudson, county of Middlesex, State of Massachusetts, have invented an Improvement in Overshoes, of which the following description, in connection with the accompanying drawing, is a specification, like characters on the drawing representing like parts.

This invention relates to improvements in overshoes and the object thereof is to provide a heel having a neck portion of smaller cross sectional area than the tread portion of the heel adapted to conform to the contour of the heel of the shoe and thereby to present a better appearance and also by gripping the neck portion of the shoe to retain the overshoe more firmly in place.

More specifically the invention relates to improvements in overshoes for ladies' "French heel" shoes, comprising a heel which will substantially conform to the curvature of the "French heel"; the heel of said overshoe being provided with means which will allow the neck of the overshoe to expand sufficiently to permit the introduction of the heel and which will act, when the overshoe is applied to the shoe, to retain the overshoe firmly upon it.

A further object of the invention is to provide a novel form of overshoe having a heel which will retain the overshoe upon the shoe whether the overshoe is provided with a full vamp, or with merely a sufficient toe portion to grip the edges of the sole and the tip portion of the shoe.

Other objects and features of the invention will more fully appear from the following description and the accompanying drawings and will be pointed out more particularly in the annexed claims.

A preferred embodiment of the invention is illustrated in the accompanying drawings, in which,

Figure 1 is a perspective view of an overshoe having a toe portion adapted to grip the edges of the sole and the tip of the shoe and a heel shaped to conform to the "French heel" of a lady's shoe.

Fig. 2 is a similar view of an overshoe having a full vamp and a heel adapted to conform to the contour of a "French heel," a portion of the heel being broken away to show the novel construction thereof.

Fig. 3 is a vertical sectional view of the

heel portion of an overshoe, embodying my invention, in the act of being applied to the "French heel" of a shoe.

Fig. 4 is a transverse sectional view on lines 4—4 Fig. 2 showing the neck portion of the heel expanded to permit the introduction of the tread portion of the heel of the shoe therethrough.

In the usual construction of rubber overshoes, particularly for ladies' shoes, the toe portion of the shoe is so constructed as to fit the toe of the shoe, while the heel portion is of sufficient cross sectional area to permit the tread of the heel to be readily introduced through it, the rubber being retained upon the foot by reason of the fitting of the rear portion of the overshoe over the curved rear portion of the heel. In the usual construction, therefore, the overshoe does not conform to the contour of the neck portion of the heel which in ladies' shoes having "French heels" usually presents a concaved surface at the sides and rear of the heel. Consequently the overshoe presents an awkward and unpleasing appearance.

The present invention contemplates the production of an overshoe having a heel which will conform to the curvature of the neck portion of the "French heel" so that when the overshoe is applied, the appearance of the foot will be as graceful as if it were without the overshoe.

This is accomplished by providing the neck portion of the heel with an elastic section which will stretch sufficiently to allow the introduction of the larger tread portion of the heel of the shoe and will immediately contract after the heel is inserted in such a manner as to fit tightly around the neck portion of the heel.

Such a construction, furthermore, is very advantageous in that it provides an additional gripping means for holding the overshoe firmly in place so that the overshoe will not become detached even though the material of the body of the shoe stretches more or less by reason of long usage.

The overshoe illustrated in Fig. 1 of the drawing comprises a toe portion having a sole 1 and edges 2, 3 of sufficient height and so curved as to grasp around the margin of the sole of the shoe and a toe 4 which extends merely over the tip of the shoe. It comprises a heel portion 5 having a downwardly extending neck 6 and a tread por-

tion 7, the tread portion of the overshoe being adapted to fit the tread of the shoe and the neck portion 6 tapered or preferably concavedly curved to provide a smaller 5 cross sectional area for the neck of the heel than that of the tread portion 7.

The neck portion of the heel is slitted and the walls of the slits secured together by an elastic section. As illustrated in Fig. 1 a 10 vertical slit 8 is provided preferably centrally of the breast of the heel and the walls of the slit are connected together by an overlying elastic member 9 of waterproof material, preferably pure rubber which is 15 vulcanized to the walls of the slit so that when the heel is introduced the elastic section may stretch sufficiently to allow the walls of the slit to separate and thereby to permit the introduction of the heel. A similar slit 20 may be provided at the rear of the neck of the heel and covered by a back-stay of elastic material, or both the breast of the heel and the back may be slitted and covered by sections of elastic material within the 25 scope of my invention.

In Fig. 2 an overshoe is illustrated as comprising a sole 10, a full vamp 11, and a heel 12, having a neck portion 13 of smaller cross sectional area than that of the tread 30 portion 14. A vertical slit 15, (see Fig. 4) is provided at the rear of the neck portion and a back-stay 16 of highly elastic waterproof material of greater elasticity than the body of the overshoe is vulcanized to the 35 walls 17 and 18 at the opposite sides of the slit.

Inasmuch as the body of the overshoe is usually constructed of fabric having waterproofed coating of rubber or similar material, it is not of sufficient elasticity to enable 40 the tread of a "French heel" to be introduced into the overshoe if the heel of the overshoe is shaped to conform to the contour of the heel of the shoe. However, by 45 providing a back-stay of pure rubber, or other highly elastic material, to cover the slit 15 sufficient elasticity is provided to enable the heel of the shoe to be readily inserted into the overshoe.

50 If desired a similar slit 19 may be provided at the breast of the heel and covered by a strip 20 of similar highly elastic material vulcanized, or otherwise secured, to the walls 21 and 22 of the breast of the shoe 55 upon opposite sides of the slit 19.

Ordinarily sufficient elasticity may be provided for the neck portion of the heel by the back-stay which covers the slit in the rear, but it will be understood that as many slits 60 may be provided in the fabric body of the heel as may be necessary, and that the elastic covering may be of such width as to cover the slit or slits, or if desired may extend entirely around the neck portion of the 65 heel to present a pleasing appearance.

It will be understood that while the invention is disclosed herein as applied to ladies' shoes having high "French heels," having necks presenting concaved outer walls, the invention is adapted to be applied to other classes of shoes in which the heels present substantially straight walls, since overshoes having heels with neck portions of smaller cross sectional area than the treads will fit tightly upon the heels above 75 the tread portion in such a manner as to conform more closely to the contour of the heels than in overshoes heretofore constructed, and, furthermore, will have the additional advantage of providing a gripping 80 of the heel which will prevent the overshoe from becoming detached.

Having thus described my invention, what I claim as new and desire to secure by Letters Patent, is:

1. An overshoe comprising a heel having a tread portion and a neck portion of smaller cross sectional area than said tread portion, said neck portion being provided with a section of greater elasticity than the body of 90 the heel adapted to allow sufficient expansion of said neck portion to permit the introduction of the heel of the shoe.

2. An overshoe comprising a heel having a tread portion and a neck portion of smaller cross sectional area than said tread portion, the wall of said neck portion being slitted and the walls of the slit connected by an elastic material adapted to allow sufficient expansion of said neck portion to permit the 100 introduction of the heel.

3. An overshoe comprising a heel having a tread portion and a neck portion of smaller cross sectional area than said tread portion, the wall of the breast of the heel being provided with a slit and the walls of the slit connected by an elastic material adapted to allow sufficient expansion of the neck to permit the introduction of the heel.

4. An overshoe comprising a toe and heel 110 of waterproof fabric, said heel having a tread portion and a neck portion of smaller cross sectional area than said tread portion, said neck portion having a slit in the back thereof and a back-stay of elastic material 115 overlying said slit and connected to said neck portion.

5. An overshoe for shoes having "French heels" having a tread portion and a neck portion presenting a concavedly curved 120 outer wall, comprising a tread portion adapted to fit the tread of the heel, and a concaved neck portion to fit the neck of the heel of the shoe, said neck portion having a vertical slit at its rear, and a back-stay of 125 elastic material overlying said slit adapted to allow sufficient expansion of said neck portion to permit the introduction of the heel and upon contraction to cause the heel of the overshoe to fit the heel of the shoe. 130

6. An overshoe comprising a toe portion having a sole provided with marginal flanges to engage the edges of the sole of the shoe, a heel having a neck portion of smaller cross sectional area than the tread of said heel and shaped to conform to the contour of the heel of the shoe, said neck portion being provided with a vertical slit and a covering of elastic material secured to the

neck portion of the shoe upon opposite sides 10 of the slit adapted to allow said neck portion to expand sufficiently to permit the introduction of the tread portion of the heel of the shoe therethrough.

In testimony whereof I have signed my 15 name to this specification.

HERMAN WESTLING.
